WAVE GUIDE STRUCTURE

Lewis Tonks, Schenectady, N. Y., assignor to General Electric Company, a corporation of New York

Application February 14, 1944, Serial No. 522,241

13 Claims. (Cl. 178—44)

1

My invention relates to ultra high frequency systems and, in particular, to apparatus for coupling an ultra high frequency generator to a wave guide of the hollow pipe type. It is an object of my invention to provide an improved electric discharge device to wave guide coupling.

It is an object of my invention to provide a coupling arrangement between a magnetron generator and a wave guide of the hollow pipe type which is particularly suited for the transmission of a large amount of power at a very short wave length.

Another object of my invention is to provide a coupling arrangement between an ultra high frequency generator of variable frequency and a dielectric wave guide of the hollow pipe type which transmits power equally well over a broad band of frequencies.

One of the features of my invention consists in an arrangement whereby a tapered transition section is interposed between a magnetron generator and a wave guide of the hollow pipe type, the cross-section of the transition section being dimensioned and shaped, at longitudinally positioned points, so that uniform wave guides having such cross sections all have substantially the same cut-off frequency, said cut-off frequency being the same as that of the uniform wave guide fed by said tapered section. Moreover, the cross-sectional area at longitudinally positioned points is dimensioned to effect a gradual transition in impedance between the magnetron generator and the output wave guide.

The features of the invention desired to be protected herein are pointed out in the appended claims. The invention itself, together with its further objects and advantages, may best be understood by the following description taken in connection with the drawings in which Fig. 1 is a vertical section of a magnetron device and a coupling arrangement suitably embodying the invention; Fig. 2 is an end view serving to illustrate the magnetron structure employed in the device of Fig. 1; Fig. 3 is an end view of the coupling arrangement of Fig. 1; Fig. 4 is a longitudinal section taken along the axis of one of the apertures of the coupling arrangement; Fig. 5 is another view of the anode employed in the magnetron of Fig. 1 showing the output arrangement; Fig. 6 is a view of a uniform wave guide having a cross

2

section similar to that of the wave guide coupling; Fig. 7 is a curve illustrating certain characteristics of the wave guide shown in Fig. 6; and Figs. 8-14 illustrate other configurations of the cross section of the tapered coupling arrangement of my invention.

Referring particularly to Fig. 1, there is shown an ultra high frequency generator 10 of the magnetron type which provides electromagnetic waves of a predetermined frequency and mode to a dielectric wave guide 11 of the hollow pipe type. The electromagnetic waves from the generator 10 are transmitted to the wave guide 11 through a wave guide coupling 12 which is dimensioned to afford the same cut-off frequency to electromagnetic waves at longitudinally positioned points, as well as to provide a gradual transition in impedance between the magnetron output and the wave guide 11.

While my improved coupling arrangement may be employed with any suitable ultra high frequency generator, one suitable device is shown in Fig. 1 as the magnetron 10 which comprises an elongated cylindrical container, the lateral wall structure of which is provided by a single metallic tube 13 consisting of ferromagnetic material, such as cold rolled steel or the like. Opposite ends of the container are similar in construction and are closed by flanged members 14 which are welded or otherwise hermetically joined to the inner surface of the part 10. Within the container and approximately at its central region, there is provided an anode structure 15 shown in plan view in Fig. 2. This anode structure comprises a circular metallic member which has a relatively large central opening 16 and a series of smaller openings 17 arranged symmetrically about the central opening, and the central opening 16 is joined to the openings 17 by means of laterally extending slots 18. Alternate ones of the metallic walls or anode posts between the slots 18 are electrically connected together by means of conductive straps 19.

Within the opening 16 of the anode structure, as shown in Fig. 1, there is provided an indirectly heated cathode comprising a sleeve 21 of nickel or other suitable material having flanges 22 spun up at its extremities. This sleeve, which may be coated externally with a suitable activating material such as barium oxide, contains a fila-

mentary heater 24 by which it may be maintained at an emissive temperature. One end of the cathode sleeve is closed by a metal disk 25, while an apertured disk 26 partially closes its other extremity.

In the operation of the device, a space charge is assumed to be developed in the space between the cathode sleeve 21 and the surrounding anode structure by the application of a suitable potential impressed between the cathode lead-in wire 28 and the container 10 to which the anode structure is directly conductively connected. The electrons which compose this space charge are given a spiral or orbital motion by a magnetic field produced by means to be described hereinafter, and their resultant gyrations about the cathode produce excitation of the anode structure at its resonant frequency. The functioning of the anode structure in the latter connection may be explained from one point of view by considering that it is made up of a plurality of mutually coupled resonant units, in each of which inductance is provided by the wall surface bounding one of the circular openings 17 and capacitance is provided by the opposing surfaces of one of the slots 18. Taking this viewpoint, it is seen that the operating frequency is determined in a large measure by the dimensions of the openings 17.

For the purpose of providing a magnetic field of sufficient intensity to permit the apparatus to function in its intended fashion, there are provided within the container 13 tapered magnetic pole pieces 30 and 31 which are directed axially of the container and which extend in close proximity to the upper and lower surfaces of the anode structure 15. These pole pieces are permanently magnetized in such sense that the north pole of one faces the south pole of the other. In order to assure the existence of a magnetic field of the required intensity, the pole pieces 30, 31 are constituted of a magnetizable substance having a high coercive force and a high energy factor. One material which may be used in this connection is that known as Alnico, a name designating a particular class of alloys of aluminum, nickel, and cobalt. As an alternative structure, instead of using permanent magnets for pole pieces 30, 31, soft iron pole pieces may be used and may be magnetized by means of an external winding (not shown).

In order to provide a low reluctance connection between the basic extremities of the respective pole pieces and the lateral wall of the container 13, the pole pieces may be respectively seated upon relatively thick disk-like members 33 consisting of ferromagnetic material, such as steel, and may be secured to these members by means of a clamping ring 34 slipped over the pole pieces and welded to the members 33. The base member 33 is of such diameter as to fit snugly within the tubular container 13 so as to provide a low reluctance connection with that part and is welded to the associated closure member 14.

Accurate spacing of the pole pieces 30, 31 with reference to the anode structure 15 may be obtained by the use of spacing rings 36 interposed between anode structure 15 and the surface of an apertured disk 37.

The wave guide 11 is illustrated as a hollow pipe having a rectangular cross section and defined by conductive side walls 40 and conductive top and bottom walls 41, 42. It is well known that ultra high frequency electromagnetic waves may be propagated dielectrically through such a hollow-pipe type wave guide where the

frequency of the exciting electromagnetic waves is greater than a critical minimum frequency which, in turn, is determined principally by the transverse dimensions of the guide. The guide is preferably constructed of a conductive material, such as copper or brass. Many types of high frequency electromagnetic waves may be transmitted through such hollow-pipe type guides. These waves have been generally indicated heretofore as being of the TE and TM types. The TM type waves have both a longitudinal and transverse component of electric field but only a transverse component of magnetic field, whereas the TE type waves have both a longitudinal and transverse component of magnetic field but only a transverse component of electric field. Electromagnetic waves of this type may be extracted from a magnetron, such as the illustrated magnetron 10. Although my invention is applicable to systems for transmitting a greater variety of waves, in describing my invention hereinafter reference will be made particularly to the TE₀₁ type of wave.

In order to provide means for directly coupling electromagnetic waves generated in the magnetron 10 to the wave guide 11 the transition coupling section 12 is interposed between the wave guide 11 and the magnetron 10. The tapered transition section 12, as seen in Fig. 3, comprises a metallic member 44 whose cross section has two substantially circular apertures 45, 46 therein connected together by a rectangular slot 47. The size of the holes 45, 46 and of the slot 47 increases uniformly from the end of the member 12 connected to the magnetron to its point of connection with the wave guide 11.

The transition section 12 may be constructed by forming two semi-circles at the wave guide end of metallic member 44, each semi-circle being tangent substantially to three sides of the rectangular wave guide 11. The two semi-circles are connected together by two straight edges 49, 50, as shown in Fig. 4. At its opposite end the member 44 is provided with an orifice comprising two symmetrically positioned holes 51, 52 joined together by a rectangular slot 53, as shown in Fig. 3. The member 44 may then be bored with two conical holes which fit the large semi-circles at the wave guide end of the member and the circles 51, 52 at the magnetron end of the member. The partition between the hollow cones is then cut away so that every cross section is of dumb-bell shape and of such proportions that a uniform guide of that same cross section would have a cut-off frequency substantially equal to the wave guide cut-off frequency. At the same time, the coupling member 12 effects a gradual change in impedance between the impedance at its magnetron end, where its value is such that it provides optimum coupling with the cavity resonator of the magnetron, and the impedance at its wave guide end, where its value matches that of the wave guide 11.

For purposes of transmitting electromagnetic energy from the magnetron into the coupling section 12, the anode 15 is flattened at one point to provide a flat wall 55, as shown in Fig. 5, against which the left-hand end of the coupling section 12 abuts. The flat wall 55 of the anode is provided with an output orifice of dumb-bell shape which comprises two circular openings 56, 57 equal in diameter to the openings 51, 52 of coupling 12 and connected by a rectangular slot 58 which coincides with the slot 53 of coupling member 12. The cylindrical

tank 13 may be provided with an aperture overlying the wall 55 of anode 15 through which a constricted portion 60 of coupling member 12 projects. The coupling member 12 may be secured to tank 13 of the magnetron in any suitable manner, as by welding or brazing.

At its point of connection with wave guide 11, the coupling member 12 may be sealed to the wave guide through a dielectric window 61, as shown in Fig. 1. The window 61 may be sealed across a rectangular opening in a metal wall 62, constructed of a suitable alloy, such as an iron-nickel-cobalt alloy, to facilitate sealing of the window thereto. Wall 62 is interposed between the abutting ends of coupling member 12 and wave guide 11, being brazed or welded to member 12. A conductive strap 63 welded or brazed to both members 11 and 12 strengthens the joint. Window 61 is provided with a shoulder portion 64, which fits into a corresponding shoulder in wall 62 on the high pressure side thereof, to strengthen the glass to metal seal. After the window 61 is sealed in place, the magnetron and the coupling unit 12 may be evacuated through an exhaust tubulation 69 connected to the bottom of the magnetron structure.

The operation of the wave guide coupling unit 12, as well as its dimensioning, may be better understood from the following description of the propagation characteristics of the dumb-bell cross section wave guide, which, in tapered form, constitutes the coupling unit. To assist in this explanation, reference is made to Fig. 6 of the drawing wherein the circular openings 51, 52 are shown as having a diameter d . The distance between the centers of the circular openings 51, 52 is designated as the dimension l . The length of the slot 53 is shown as equal to 26 and the height of this slot as having a value t . The angle subtended by half of the gap 53 at the center of one of the holes 51, 52 is equal to α .

The curves in Fig. 7 have been derived by the suitable application of Maxwell's equations to the propagation space of the wave guide shown in Fig. 6. These curves give the dimensions of cross sections which produce a cut-off wave length of 10.0 centimeters. For example, a cross section in which $t=0.18$ inch, $l=0.5$ inch, and $d=0.2$ inch, has its cut-off at 10 centimeters, because for it $d/l=0.4$, and following the $d/l=0.4$ line 70 on Fig. 7 to its intersection with the $l=0.50$ curve, it is seen that that intersection lies also on the $t=0.18$ inch line.

Certain approximations have to be made in the mathematical theory leading to Fig. 7, with the consequence that the curves are substantially valid over a limited region which is defined by the dashed curves labelled $\alpha=0.5$ radian and $t=l-d$.

It is well known that to apply a set of curves, such as those of Fig. 7, to a structure having a cut-off wave length of λ centimeters, different from 10 centimeters, it is only necessary to multiply the actual dimensions by $10/\lambda$ thereby obtaining scaled values to which Fig. 7 is applicable.

By way of illustrating the procedure of obtaining from Fig. 7 the dimensions for a tapered wave guide coupling section, consider an actual example in which the wave guide 11 of Fig. 1 is 1.44 inches $\times$ 2.84 inches, inside dimensions, the tapered section 12 is 4 inches long from magnetron block 15 to wave guide 11, and the orifice 56, 57, 58 at the small end is approximately 1 inch long over all.

The 2.84 inch dimension of the wave guide immediately fixes the cut-off wave length λ_0 as 14.5 inches.

centimeters. If we assume a given slot thickness for slot 58 and a value for the dimension t , the curves of Fig. 7 enable us to calculate the dimension d . Assumption of a sequence of values for t and l enables us to reach the following set of values which are consistent with Fig. 7 and which are primed to distinguish them from actual dimensions:

$$\begin{aligned} l' &= 0.50 \\ d'/l' &= 0.38 \\ l'+d' &= .69 \\ t' &= 0.012 \end{aligned}$$

When multiplied by the ratio 14.5/10, the desired values are given as

$$\begin{aligned} l_1 &= .725 \\ d_1 &= .276 \\ t_1 &= .0174 \\ l_1+d_1 &= 1.001 \end{aligned}$$

where the subscripts denote that these dimensions apply at the small end, and where the final value of the set shows that the over-all length of the guide section is approximately 1 inch. These dimensions fix the small or magnetron end of the tapered section.

The large or wave guide end of coupling 12 is fixed by the wave guide dimensions:

$$\begin{aligned} d_2 &= 1.44 \\ l_2+d_2 &= 2.84 \\ l_2 &= 1.40 \end{aligned}$$

Since the circular arcs at the large and small ends are joined by conical surfaces, it follows that for any cross-section a fractional distance f (shown in Fig. 4) from small to large end

$$\begin{aligned} l_f &= l_1 + f(l_2 - l_1) & (1) \\ d_f &= d_1 + f(d_2 - d_1) & (2) \end{aligned}$$

It is then possible to construct the following table:

	1	2	3	4	5	6	7	8
45 1	f	0	0.1	0.2	0.3	0.4	0.5	1.0
2	d_f	.276	.392	.509	.625	.742	.858	1.440
3	l_f	.724	.752	.859	.927	.994	1.067	1.400
4	d_f/l_f	.382	.495	.592	.675	.747	.805	-----
5	l_f'	.499	.545	.591	.639	.685	.735	-----
6	t'	.012	.021	.042	.070	.107	.145	-----
7	t	.0174	.0305	.061	.101	.155	.210	1.440

The values of f in horizontal row 1 are chosen conveniently and arbitrarily. Rows 2 and 3 are calculated by Equations 1 and 2. Row 4 follows from rows 2 and 3. Row 5 is obtained by multiplying row 3 by the ratio 10/14.5 as previously explained. Row 6 is taken from Fig. 7 using rows 4 and 5, except in vertical column 8 which applies to the rectangular wave guide. Row 7 is row 6 multiplied by 14.5/10.

Thus the dimensions of the coupling section are complete up to half the distance from the small or magnetron end to the wave guide end. It is seen, however, that Fig. 7 does not apply beyond $f=0.5$ so that another consideration has to be used. The curve of t against f in Fig. 4 is continued as a smooth curve to $t=1.44$ at $f=1$, that is, at the wave guide junction, as indicated in Fig. 4.

In connection with the foregoing illustration, it is pointed out that, while the length of 4 inches used in the illustration is approximately equal to a 10-centimeter wave length of the wave propagated in the guide, the length of the transition section 12 is not necessarily thus related to the wave length of the electromagnetic wave

being propagated. Instead, the over-all length of the transition section 12 may be any value which gives an essentially smooth variation of impedance over a length greater than approximately $\frac{1}{6}$ of a wave length in free space. Of course, the cut-off wave length at every cross section, that is, the cut-off wave length of a uniform wave guide having this particular cross section, must be greater than the wave length of the wave being propagated. Another important advantage of the coupling arrangement is that the gradually tapered section provides an essentially smooth transition in impedance so that the coupling section is substantially reflectionless at all points beyond approximately $\frac{1}{6}$ of a wave length from the point of connection to the ultra high frequency generator.

While in the illustrations and discussion thus far the cross section of the coupling member 12 has been described as being substantially dumb-bell in shape, the cross section of the section 12 need not be limited to this particular shape and any other suitable cross section may be employed, the apertures in the member tapering from the point of connection to the ultra high frequency device to the end connected to the wave guide 11. In Figs. 8-12, there are shown other configurations of cross sections for the coupling member 12, all of which employ a pair of apertures 80, 81 connected by a slot 82. Each of the apertures and the slot are tapered between the two ends of the coupling member 12. Fig. 11, for example, shows a cross section which is rectangular in form and Fig. 12, one which is octagonal in form.

In Fig. 13, there is shown a cross section for the coupling member 12 in which the two tapered apertures 80, 81 are not of the same size so that the symmetry of form illustrated in the preceding cross section views of the coupling member 12 is not present in this particular form of coupling member. A similar asymmetrical condition may be employed in coupling members using circular apertures, as well as members using rectangular apertures, as in Fig. 13. In Fig. 14, the slot connecting the tapered apertures 80, 81 is of a sinuous type and consists of a pair of parallel passages 83, 84 and a connecting passage 85. Configurations in the cross section of a coupling unit of this type are especially desirable where the cut-off frequency of the wave being propagated is relatively low so that extremely large wave guide sections would be required.

It is apparent, moreover, that, while the wave guide 11 is illustrated as of the rectangular type, the coupling member 12 may be employed to connect the output of an ultra high frequency device to a wave guide of any given configuration, the criteria being that the cut-off wave length at every cross section must be greater than the wave length of the electromagnetic wave being propagated and that a gradual transition impedance be effected between the two ends of the coupling unit to effect a match with the impedance of the wave guide connected thereto. Such a coupling is particularly suited for the transmission of large amounts of energy of relatively short wave length.

While I have shown a particular embodiment of my invention, it will of course be understood that I do not wish to be limited thereto since various modifications may be made, and I contemplate by the appended claims to cover any such modifications as fall within the true spirit and scope of my invention.

What I claim as new and desire to secure by Letters Patent of the United States is:

1. A wave guide of the hollow pipe type defined by a block of metal provided with a tapered longitudinal opening, every cross section of said opening taken at longitudinally positioned points thereof comprising a narrowed central portion and being dimensioned so that a uniform wave guide of said cross section would afford the same cut-off frequency to electromagnetic waves.

2. A coupling device for an ultra high frequency transmission system comprising a conductive member defining therein a tapered longitudinal opening the cross-sectional area of which at longitudinal points comprises a narrowed central portion and is dimensioned to have a predetermined variation in impedance along the longitudinal axis.

3. A coupling device for use in an ultra high frequency transmission system comprising a conductive member having a tapered longitudinal opening extending therethrough the cross section of which at one end is defined by an elongated central opening terminated at each end in an enlarged opening the last mentioned openings progressively increasing in cross-sectional area in the longitudinal direction.

4. A dielectric wave guide of the hollow-pipe type comprising a block of metal having therein a tapered longitudinal opening the cross sectional area of which at one end includes a central elongated slot terminated at each end thereof in an enlarged circular opening, the last mentioned openings progressively increasing in cross sectional area in the longitudinal direction.

5. In combination, a dielectric wave guide of the hollow-pipe type comprising a conductive member of rectangular cross section, an ultra high frequency generator comprising a cavity resonator, and means for coupling said wave guide and said cavity resonator comprising a conductive member having therein a tapered longitudinal opening the cross sectional area of which at longitudinal points comprises a narrowed central portion and is dimensioned to effect a gradual transition in impedance.

6. In combination, a wave guide of the hollow pipe type, an ultra high frequency generator comprising a cavity resonator, and means for coupling said wave guide and said cavity resonator comprising a conductive member having a length greater than $\frac{1}{6}$ of a free space wave length of an electromagnetic wave in said generator, said member having therein a tapered longitudinal opening, the cross sectional area of which at longitudinal points comprises a constricted central portion and is dimensioned to effect gradual transition in impedance.

7. In combination, an ultra high frequency generator of the space resonant type comprising a metallic member for defining a cavity resonator, said member being provided with an aperture through which high frequency energy may be extracted, a dielectric wave guide of the hollow pipe type, and coupling means for connecting said generator to said wave guide comprising a metallic member having therein a tapered longitudinal opening the cross sectional area of which at longitudinal points comprises a constricted central portion and is dimensioned to have a substantially uniform cut-off characteristic and having at one end adjacent said generator a geometry similar to said aperture.

8. In combination, an ultra high frequency magnetron of the space resonant type comprising

ing a plurality of electrodes including an anode structure for defining a cavity resonator, said anode structure being provided with an aperture comprising a central slot terminated at the ends in circular openings, a dielectric wave guide of the hollow pipe type having a rectangular cross section, and coupling means between said anode structure and said wave guide comprising a conductive member having a tapered longitudinal opening the cross sectional area of which is dimensioned at one end adjacent said anode structure for optimum coupling to said cavity resonator and dimensioned at the other end to match the impedance of said guide.

9. In combination, an ultra high frequency magnetron of the space resonant type comprising a plurality of electrodes including an anode structure for defining a cavity resonator, said anode structure being provided with an aperture, a dielectric wave guide of the hollow pipe type, and coupling means between said anode structure and said guide comprising a conductive member having a tapered longitudinal opening the cross sectional area of which comprises a narrowed central portion and is dimensioned to have a transitional impedance which provides optimum coupling to said cavity resonator and impedance matching with said guide.

10. In combination, an ultra high frequency generator of the space resonant type including a structure for defining a cavity resonator, said structure being provided with an aperture through which the energy of said cavity resonator may be extracted, a dielectric wave guide of the hollow pipe type, and coupling means between

15

said structure and said wave guide comprising a conductive member having a tapered longitudinal opening the cross sectional area of which comprises a narrowed central portion and is dimensioned to afford a transitional impedance which provides optimum coupling to said cavity resonator and impedance matching with said wave guide.

11. A dielectric wave guide of the hollow pipe type defined by a block of metal having a longitudinal opening comprising a pair of longitudinal tapered openings joined by an intermediate slot, the separation of opposing faces of said slot increasing with the cross sectional area of said tapered opening.

12. A dielectric wave guide of the hollow pipe type defined by a block of metal having a longitudinal opening comprising a pair of longitudinal conical openings joined by an intermediate slot the separation of opposing faces of which increases in accordance with the cross sectional area of said conical openings.

13. A discharge device for an ultra high frequency transmission system comprising a conductive member defining therein a tapered longitudinal opening comprising a pair of longitudinal conical openings joined by an intermediate slot the separation of opposing faces of which increases in accordance with the longitudinal cross sectional area of the conical openings to produce at one end a substantially rectangular opening for connection to a dielectric wave guide of the hollow pipe type.

LEWI TONKS.
